UNITED STATES PATENT OFFICE.

ABRAHAM S. ADLER, OF BALTIMORE, MARYLAND.

CONFORMATOR.

SPECIFICATION forming part of Letters Patent No. 482,911, dated September 20, 1892.

Application filed November 5, 1891. Renewed August 24, 1892. Serial No. 443,944. (No model.)

To all whom it may concern:

Be it known that I, ABRAHAM S. ADLER, a citizen of the United States, residing at the city of Baltimore, State of Maryland, have invented certain new and useful Improvements in Conformators, as set forth in the accompanying drawings, forming part of this specification, in which—

Figure 1 represents a perspective view of a conformator embodying my invention. Fig. 2 is a transverse sectional view of the same on the line xx of Fig. 3. Fig. 3 is a longitudinal sectional view on the line yy of Fig. 2. Fig. 4 is a plan view of a diagram used in connection with the conformator. Fig. 5 is a modification to be referred to.

My invention relates to means for obtaining the exact measure and contour of forms—such as lasts—and in transmitting the outline of the form or last to a diagram or sheet having lines and characters corresponding to the last or parts of the human foot; and it consists of the constructions, arrangements, and combinations of devices which I shall hereinafter fully describe and claim.

To enable others skilled in the art to which my invention appertains to make and use the same, I will now describe its construction and indicate the manner in which the same is carried out.

In the accompanying drawings, A represents the vertical sides of the machine separated from each other a distance sufficient to permit the introduction between them of the largest size of lasts and having the surfaces slotted in parallel vertical lines, as shown at a . At their upper portions these side pieces are firmly connected by means of transverse connecting-rods B, while at the ends of the lower portions of the sides are transverse uniting-bars C for connecting the lower portions of the bars and giving the desired strength and rigidity to the structure.

To the end cross-bars C vertical standards D are pivotally secured or hinged, so that they may be turned into a horizontal position to permit the last to be introduced into or removed from the machine. These end standards are slotted longitudinally at b to receive a pin or rod c, which extends through the slot and is adapted to enter recesses or holes at opposite ends of the last, as shown in Fig. 3,

and said pins or rods c may be adjusted vertically in the slotted standards to raise or lower the suspended last in the machine, and 55 may also be adjusted horizontally in and out to accommodate different lengths of lasts, these adjustments being maintained by means of set-screws d, or other similar means, working in slots made transversely through the 60 standards D, as shown in Figs. 1 and 3.

Passing transversely across the machine and mounted to freely slide in the slots in the sides thereof are the rods E and F, each of which has its ends extended beyond the outer 65 surfaces of the sides A, said rods having one end pointed and the other threaded to receive a nut e or analogous device, adapted to bear against a spring G, interposed between the inner surface of the nut and outer surface of 70 the side A, whereby each pin is maintained in a horizontal position, while the friction of the spring against the side A is sufficient to hold the pin and its adjuncts in any position they may be placed in the slots a . These rods 75 E and F are arranged in two series, those of one series E occupying the upper portions of the slots a and those of the other series F occupying the lower portions of said slots, while the inserted last occupies the central portion 80 of the machine between the two series of rods. When the last is thus inserted, the rods of the upper series are moved down upon the last and those of the lower series are moved up against the under part of the last, when their 85 combined outer or pointed ends will disclose a perfect counterpart or fac-simile of the contour of the last.

On the transverse rods E are mounted sliding blocks H, having depending pointed pins 90 g, adapted to be pressed down upon the last along its central or median line when the rods are moved down in their slots, and upon the lower rods F are sliding blocks I, preferably two on each rod, having pointed pins i i' projecting from their upper and lower surfaces. From this description it will be seen that when the last is placed in position and suspended by the rods at its toe and heel portions the upper series of rods E is moved down and the 100 sliding blocks adjusted thereon until their pins engage the upper middle line of the last. The blocks on the lower series of rods F are moved toward the ends of the rods and then

moved up close to the sides of the last, so that when the rods are raised upwardly toward the last the pointed ends of the pins *i* will fit snugly the under part of the last to give the under shape of the last to the pointed extremities of the rods *F*. The lower set of pins *i'*, projecting downwardly from the sliding blocks, will also, by reason of the adjustment above noted, indicate the exact tread or contour of the last, which shape or contour is readily transferred to a diagram or sheet placed below the pins and brought into contact with the pointed ends of the pins in any well-known manner.

15 In order that the longitudinal shape of the last may be preserved for future reference, I pivotally secure or hinge to the lower side of that side of the machine which receives the pointed ends of the rods *E* and *F* a platform or plate *M*, having a soft yielding surface on one side. Upon this yielding surface a diagram or sheet *N*, similar to that shown in Fig. 4, is placed, and when the platform or plate *M* is raised from its horizontal position into 25 a vertical position and pressed against the protruding pointed ends of the adjusted rods *E* and *F* these ends perforate the sheet in lines corresponding with the shape of the last.

In order that the exact length or number of 30 the last may be made known, the diagram is provided with a series of parallel lines *m* at both its toe and heel portions, with characters indicative of sizes of last from small 12 to large 12. This form of diagram enables me to accurately 35 note the size and shape of a heel or toe larger than usual or where the heel or toe is longer than the recognized standard as found in the lasts usually employed in shoemaking. The diagram may also have other 40 lines *n* upon it between the heel and toe portions, and extending from a point indicating the cuboid bone toward the toe portion and lettered from *A* to *I* to indicate the width of last. In addition to the foregoing the diagram 45 may also have lines or spaces, in which may be written or marked the words "Heel," "Ankle," "Leg," "Instep," "Spring," "Lot," "Kind," "Toe," and "Heel," so that when the measurements are taken and the shape of the last ascertained a complete record of the foot is 50 known and may be preserved for future use.

In Fig. 5 is shown a modification of the standards at the front and rear of the apparatus. This form of standard may be substituted for those shown in Figs. 1 and 2, and it comprises a nut *r*, working between two horizontal spaced bars *s* in the lower portion of the machine and having a screw *t* passing vertically through it, with a pin *u* projecting 60 from its upper end and engaging the last near its ends, whereby the latter is supported in substantially the same manner as before described. When these screws are not in use, they may be run down until their pointed pins are flush with or below the upper plane 65 of the bars *s*, so as not to be in the way.

Having thus described my invention, what

I claim as new, and desire to secure by Letters Patent, is—

1. In a conformator, transversely-mounted vertically-slidable rods arranged in upper and lower series and adapted to delineate the outlines of a last introduced between them.

2. In a conformator, a frame vertically-slotted, an upper and lower series of vertically-adjustable horizontal rods slidable in said frame, and a last or form adapted to be introduced between the rods of the upper and lower series.

3. In a conformator, a frame having a double series of horizontal rods mounted to slide vertically therein, the rods of one series occupying the upper part of the frame and those of the other series the lower portion of said frame, a form adapted to be introduced between said series of rods, and a diagram or sheet adapted to be brought into contact with the ends of the rods, whereby the outline of the inserted form is transferred to the diagram or sheet.

4. In a conformator, the slotted sides and the double series of rods adapted to be adjusted toward and from each other, in combination with standards at the opposite ends of the machine, rods adjustably fitted thereto, and a last or form suspended from said end rods between the double series of rods.

5. In a conformator, the slotted sides and the double series of rods held by friction and adjustably secured so that the rods of one rod series may be moved toward and from those of the other series, in combination with slotted end standards horizontally and vertically suspended from said latter rods between the double series of rods, and a diagram or sheet adapted to be brought against the ends of the double series of rods, whereby the outline of the last or form is transferred to the diagram or sheet.

6. In a conformator, the slotted sides and slotted end standards, the upper and lower series of transverse rods slidable from opposite ends of the slotted sides and having ends protruding, one of said ends having a spring and adjusting-nut and the others being pointed, and a hinged platform or plate carrying a diagram or sheet adapted to be brought against the pointed ends of the rods, whereby the outline of an object inserted between the double series of rods is indicated upon the diagram or sheet.

7. In a conformator, the slotted sides, the transverse rods mounted therein in double series, one series occupying the upper portions of the slots and the other the lower portions thereof, blocks mounted to slide upon the rods of both series and having pins adapted to be adjusted against a form introduced between said double series of rods, the blocks on the lower series of rods having pins projecting, also, from their lower sides, and diagrams or sheets adapted to be pressed against the latter pins and the ends of the double series of rods, whereby correct out-

line of the inserted form is transferred to the diagrams or sheets.

8. In a conformator, the slotted sides and the double series of transverse rods slidable therein, a form adapted to be introduced between said series of pins and against which the rods are adjusted, and a hinged or pivoted plate at one side of the machine adapted to be brought against the ends of the rods, 5 said plate having a yielding surface on which a diagram or sheet is placed.

9. In a conformator having a double series of transverse rods vertically adjustable toward and from a last suspended between them, a diagram having parallel-numbered lines at 15 opposite ends corresponding to the heel and toe portions of the last, whereby the length of the heel and toe is ascertained.
